UNITED STATES PATENT OFFICE.

DANA OSGOOD, OF HOPEDALE, MASSACHUSETTS, ASSIGNOR TO DRAPER COMPANY,
OF HOPEDALE, MASSACHUSETTS, A CORPORATION OF MAINE.

WARP STOP-MOTION FOR LOOMS.

1,116,321.

Specification of Letters Patent.

Patented Nov. 3, 1914.

Application filed February 24, 1913. Serial No. 750,350.

To all whom it may concern:

Be it known that I, DANA Osgood, of Hopedale, Worcester county, Massachusetts, have invented a new and Improved Warp 5 Stop-Motion for Looms, of which the following is a specification.

The improvements are illustrated in the accompanying drawings, in which—

Figures 1 and 2 are vertical cross-sections 10 of so much of a loom as is necessary to enable the invention to be understood, the two figures showing similar but different arrangements.

In the drawings, A, B, are two banks of 15 thin sheet metal drop bars or detectors, each detector having a longitudinal slot *a*, and a thread eye *b*; C, D, are two stationary guide bars, each of which extends through the slots *a*, in one bank or row of the detectors; E, F, 20 are upper lease rods, each of which is immediately above one of the guide bars and one of the banks of detectors; and G, H, are lower lease rods on opposite sides of and alongside the two banks of detectors. Each 25 warp thread passes through the eye *b*, of one of the detectors and normally supports that detector, which is thus suspended. There are as many detectors in both banks as there are warp threads in the loom. The 30 rods E, F, G, H, divide the warp threads into two intersecting planes, the intersection being between the two banks of detectors. The detectors are suspended from the bottom sheds. One-half the warp 35 threads pass beneath the rod E, and over the rod H, and the other half of the warp threads pass over the rod F, and under the rod G. The head of each detector is normally well below the rod above it, so that a 40 detector cannot come in contact with any thread except that from which it was suspended. Each detector is free to move vertically both up and down and laterally both ways, so that the detectors accommodate 45 date themselves to the threads and the strains thereon and chafing is reduced to a minimum.

In case a warp thread breaks, its detector drops, being guided by its guide bar C, or 50 D, and is suspended in its dropped abnormal position by the guide bar. A detector in its dropped or abnormal position effects the stoppage of the loom through any of the well known coöperating devices, electrical or

mechanical, in accordance with the known 55 teachings of the art. The coöperating instrumentalities may be electrical, such as shown, for example, in the reissued patent of Coldwell and Gildard, No. 11,923, July 30, 1901, or they may be mechanical, such as 60 shown, for example, in the patent of Ambler, No. 863,130, August 13, 1907.

The arrangement shown in Fig. 2, is similar to that shown in Fig. 1, excepting that the rods G, and H, are nearer the rods E, 65 F, and the detectors than in Fig. 1.

In the arrangement shown in Fig. 1, a detector can never come in contact with the lease rod above it or with any of the lease rods. In the construction shown in Fig. 2, 70 no detector while its weight is being supported by its thread comes in contact with any of the lease rods and, consequently, no thread can drag along its detector when its detector is held against a lease rod. 75

I claim:

1. A warp stop motion for looms having, in combination, two upper lease rods above which the two planes of the warp threads respectively pass; a detector guide directly 80 beneath each of the upper lease rods; two lower lease rods beneath which the two planes of warp threads respectively pass, each plane of warp threads which passes beneath one of the lower lease rods extending below and out of contact with the corresponding upper lease rod and guide; lower lease rods being out of line with the corresponding upper lease rod and guide; and a bank of detectors for each plane of 90 warp threads suspended therefrom immediately beneath one of the upper lease rods and being guided by the guide beneath such upper lease rod so as to be out of normal contact with any of the lease rods, there being one detector for each warp thread. 95

2. A warp stop motion for looms having, in combination, two upper lease rods above which the two planes of the warp threads respectively pass; two detector guides beneath the upper lease rods; two lower lease rods beneath which the two planes of warp threads respectively pass, each plane of warp threads which passes beneath one of the lower lease rods extending below and out of contact with the corresponding upper lease rod, and each of the lower lease rods being 100 out of line with the corresponding upper 105

lease rod and guide; and a bank of detectors for each plane of warp threads suspended therefrom beneath one of the upper lease rods and being guided by one of said guides so as to be out of normal contact with any of the lease rods, there being one detector for each warp thread.

In witness whereof, I have hereunto signed my name in the presence of two subscribing witnesses.

DANA OSGOOD.
